TAMPING AND/OR MIXING MACHINE

Benjamin H. Flynn, Alexandria, La.

Application June 29, 1938, Serial No. 216,577

16 Claims. (Cl. 94—39)

In the construction of roadways and the like, particularly those of soil-cement composition, bituminous or oil bound nature, and concrete, it is highly desirable to thoroughly tamp and/or mix the loose or plastic road material upon the grade, or road-bed. Also if the grade or bed upon which a road is to be laid, should have an excessive amount of loose earth, such earth should be thoroughly compacted before laying the road material. Present-day road building and maintenance machines have been found inadequate for these purposes and the present invention aims to provide a new and improved mechanism for effectively and economically obtaining the desired results, whether said mechanism be embodied in a road building or maintenance machine, or in a machine designed solely for tamping and/or mixing.

With the foregoing and minor objects in view, the invention resides in the novel subject matter hereinafter described and claimed, description being accomplished by reference to the accompanying drawings.

Figure 1 is a side elevation partly broken away and in section showing the invention embodied in a sub-grading and/or road reconditioning machine.

Figure 2 is a rear perspective view with the strip, templet or the like 46 omitted.

Figure 3 is a partial top plan view with the deck plates of the mobile frame omitted.

Figure 4 is a sectional perspective view of one of the tamping and/or mixing units and its operating means.

Figure 5 is an enlarged side elevation partly in section of the same.

Figure 6 is a perspective view showing different tamping and/or mixing members.

For illustrative purposes, the invention is shown embodied in the rear portion of a sub-grading, road reconditioning or similar machine, said machine including a tractor truck T of the crawler or endless tread type, a rigid frame structure F pivoted at P to the front axle of said truck

T, and jacks J by means of which said frame structure may be upwardly and downwardly swung with respect to said truck T, said frame carrying a conventional motor M and all required equipment for propelling and steering the machine, for driving the tamping and/or mixing means constituting the present invention, and for performing any functions required of said machine.

The side members 10 of the frame F project rearwardly beyond the truck T and are provided

with plates 11 which project downwardly sufficiently to confine the loose or plastic material 12 to be acted upon by the tamping and/or mixing means. In the present disclosure, it may be assumed that this material is produced by the operation of a rotary cutter 13 and that any desired liquid may be mixed with said material by the rotation of said cutter, said liquid being supplied through appropriate spray means 14.

On the rear end of the side members 10 I have shown vertically elongated guides 15 with which the ends of a transverse bar 16 are engaged for vertical sliding, screws 17 and hand wheels 18 being employed for vertically adjusting said bar as required. Vertically oscillatory arms 19, extending longitudinally of the machine, are pivoted at 20 to the bar 16 and extend forwardly therefrom, each arm 19 being preferably composed from two angle metal bars 19' connected by transverse angle metal bars 21, 22 and 23. To these bars 21, 22 and 23, the tamping and/or mixing members are secured to penetrate the material 12 repeatedly as the machine is propelled, the arms 19 being alternately raised and lowered to effect operation of said tamping and/or mixing members. In Figs. 1 to 5, these members are shown as consisting of blades or plates 24, 25 and 26 secured to the bars 21, 22 and 23 respectively, and disposed in substantially vertical transverse planes, the plates 25 being disposed in end-to-end-relation and preferably slightly overlapped, in a row extending transversely of the machine, and the same being true of the plates 25 and 26. Preferably the plates 24 are sufficiently long to penetrate the material 12 substantially to the grade or roadbed 27, the plates 25 are somewhat shorter to tamp the intermediate portion of the material, and the plates 26 are still shorter to tamp the surface material. While tamping is here referred to, it will be understood that the plates will not only produce a tamping action, but will tend to mix the materials as they are alternately forced into and withdrawn from the same.

Instead of using plates such as 24, 25 and 26, teeth of circular, square or other transverse section could well be employed, either with or without one or more of said plates, and in Fig. 6, I have illustrated a series of spaced vertical teeth or blades 28 substituted for the plate 24, and similar teeth or blades 29 substituted for the plate 25, the teeth or blades of the two sets being staggered with respect to each other. Due to the small cross sectional area of the teeth or blades, they may be forced into and withdrawn from the

material with the expenditure of relatively little power.

For vertically oscillating the arms 19, I provide a transverse crank shaft or similar shaft 30 driven by a chain or the like 31 and appropriate transmission from the motor M, said shaft 30 being operatively connected with said arms by connecting rods 32, the upper ends of said arms being connected with said shaft and the lower ends thereof being connected with said arms. It is preferable that the rods 32 be of extensible and retractable nature to vary the extent which the tamping and/or mixing members will be forced into the material. It is also preferable that a yielding connection be employed between the rods 32 and the arms 19 to prevent injury of parts should complete depression of any arm be prohibited by striking of any of the mixing or tamping members solidly against an obstruction. The specific construction described below, is preferably followed.

A vertical sleeve 33 is pivotally connected at its lower end with the arm 19 as shown at 34, the upper end of said sleeve being provided with a removable cap 35 having a central opening 36. The lower section 37 of the rod 32 passes slidably through this opening, said section 37 being adjustably connected with the upper rod section 38 by means of a bolt 39 engageable with any of the vertically spaced openings 40. The rod section 37 carries an abutment which preferably consists of a flange or collar 41 permanently secured on said section, and a collar 42 resting on said flange or collar 41 and removable from said section 37. Upon upward movement of the rod 32, the collar 42 abuts the cap 35, lifting the sleeve 33 and the arm 19 to withdraw the tamping and/or mixing members from the material. Under this abutment, there is a coiled compression spring 43 in the sleeve 33 resting upon the closed lower end of the latter, and upon downward movement of the rod 32, this spring forces the arm 19 downwardly to cause the tamping and/or mixing members to penetrate the material, but if the downward movement of said members should be interfered with by solidly striking any object, the spring 43 will merely compress and no injury to parts will result. By removing the collar 42 and substituting one of greater thickness, it will be seen that the state of compression of the spring 43 may be increased.

The speed of the shaft 30 may be so controlled with respect to the forward speed of the machine as to cause the various tamping and/or mixing members to advance say one-half inch more or less between blows and it is thus insured that all of the material shall be acted upon to perform the desired tamping action, the desired mixing operation, or both. The angle at which the tamping members or the like engage the material may be varied by vertically adjusting the bar 16 carrying the arms 19, and the extent which said members will penetrate the material may be changed by varying the length of the connecting rods 32, and thorough tamping and/or mixing may be effected. If the material be of slushy nature, the invention will produce very much the action of a mortar hoe on mortar, and the material is prevented from being thrown laterally by means of the plates 11. A flexible transverse strip 44 of rubbered fabric or the like may be provided to slide over the material in advance of the mixing means. In the present showing, the strip 44 is carried by a

transverse partition 45 extending between the side members 10 directly behind the cutter 13, preventing this cutter from rearwardly throwing material onto the finished road surface. Another transverse strip 46 of rubbered fabric or the like, or if desired, a templet, may be suitably secured to the rear end of the machine to impart a final smoothing to the material. Should it be desired, however, to leave a transversely ribbed formation 47 on the surface of the road, particularly if the latter be of concrete, the member 46 may be omitted and the ripples or ribs will be produced by the plates 26.

The off-center portions (cranks or eccentrics) of the shaft 30 are preferably so set that the various arms 19 lower in one sequence or another instead of all lowering simultaneously, therefore requiring the expenditure of less power and lessening the vibration in the machine.

From the foregoing taken in connection with the accompanying drawings, it will be seen that novel provision has been made for performing tamping operations mixing operations, or both in connection with road material lying in place upon a grade or roadbed, the machine being of particular advantage in the construction of roadways and the like of soil-cement composition, concrete, or bituminous or oil-bound nature. The invention is also usable to advantage in preparing grades or roadbeds for the reception of road material if they should possess an excessive amount of loose earth, for such earth can be thoroughly and expeditiously packed by means of the invention.

While excellent results may be obtained from the general construction shown and described, it may well be followed. However, within the scope of the invention as claimed, numerous variations may be made and it will be obvious that the invention may be embodied in a road building or maintenance machine, or in a machine designed solely for tamping and/or mixing.

I claim:

1. A machine of the class described comprising a mobile frame for propulsion over loose or plastic road material, a plurality of vertically reciprocable vertical blades mounted on said frame, said blades being disposed at least in a front and a rear row both extending transversely of the machine, and means for reciprocating said blades in such manner that the blades of the front row deeply penetrate the material to settle the same and tamp the lower material upon the road bed and the blades of the rear row penetrate the surface material to further settle the same and tamp it upon said lower material.

2. A machine of the class described comprising a mobile frame for propulsion over loose or plastic road material, a plurality of vertically reciprocable vertical blades mounted on said frame, said blades being disposed in a front row, a rear row and an intermediate row all extending transversely of the machine, and means for reciprocating said blades in such manner that the blades of the front row deeply penetrate the material to settle the same and tamp the lower material upon the road bed, the blades of the intermediate row less deeply penetrate to further settle the material and tamp the intermediate material upon said lower material, and the blades of the rear row penetrate only the surface material to still further settle the material and tamp said surface material upon said intermediate material.

3. A machine of the class described comprising

- ing a mobile frame for propulsion over loose or plastic road material, a plurality of arms extending longitudinally of said frame and pivoted at their rear ends thereto for vertical swinging, 5 means connected with said arms for vertically swinging the same, front blades secured to and projecting downwardly from said arms to deeply penetrate the material, thereby settling same and tamping the lower material on the roadbed, and 10 10 other blades secured to and projecting downwardly from said arms in rearwardly spaced relation with said front blades to less deeply penetrate the material, thereby further settling the material and tamping the upper material upon 15 the lower material.
4. A machine of the class described comprising a mobile frame for propulsion over road material in situ, a transverse rotary driven cutter mounted on said frame for disintegrating said material and 20 20 performing a mixing operation thereon, a plurality of vertically reciprocable vertical blades mounted on said frame behind said rotary cutter, said blades being disposed at least in a front and a rear row both extending transversely 25 25 of the machine, and means for reciprocating said blades in such a manner that the blades of the front row deeply penetrate the material to settle the same and tamp the lower material upon the road bed and the blades of the rear row penetrate 30 30 the surface material to further settle the same and tamp it upon said lower material, said blades performing additional mixing operations in addition to the settling and tamping operations performed thereby.
- 35 5. A machine of the class described comprising a mobile frame for propulsion over loose or plastic road material or the like, a transverse row of vertically oscillatory arms mounted on said frame, said arms extending longitudinally of said frame, 40 40 vertical members secured to and projecting downwardly from said arms to penetrate the material over which the machine is propelled, and means on said frame and connected with said arms for continuously oscillating the latter relatively and 45 45 to an extent to force said vertical members into and withdraw them from said material.
6. A machine of the class described comprising a mobile frame for propulsion over loose or plastic road material or the like, a transverse row 50 50 of vertically oscillatory arms mounted on said frame, said arms extending longitudinally of said frame, vertical blades in transverse planes secured to and projecting downwardly from said arms to penetrate the material over which the machine is propelled, and means on said frame and connected with said arms for continuously oscillating the latter relatively and to an extent to force said vertical blades into and withdraw them from said material.
- 55 7. A machine of the class described comprising a mobile frame for propulsion over loose or plastic road material or the like, a transverse row of vertically oscillatory arms mounted on said frame, said arms extending longitudinally of said frame, transverse plates secured to and projecting 60 60 downwardly from said arms to penetrate the material over which the machine is propelled, said plates being disposed in a row in end-to-end relation, and means on said frame and connected 65 65 with said arms for continuously oscillating the latter relatively and to an extent to force said plates into and withdraw them from said material.
- 70 8. A machine of the class described comprising a mobile frame for propulsion over loose or plastic 75 75 road material or the like, a transverse row of vertically oscillatory arms mounted on said frame, said arms extending longitudinally of said frame, a plurality of downwardly projecting blades carried by each of said arms and spaced apart transversely thereof to penetrate the material over which the machine is propelled, and means on said frame and connected with said
- tic road material or the like, a transverse row of vertically oscillatory arms mounted on said frame, said arms extending longitudinally of said frame, transverse plates secured to and projecting downwardly from said arms to penetrate the material over which the machine is propelled, said plates being disposed in a row in end-to-end slightly overlapped relation, and means on said frame and connected with said arms for continuously oscillating the latter relatively and to an extent to force said plates into and withdraw them from said material. 5
9. A machine of the class described comprising a mobile frame for propulsion over loose or plastic road material or the like, a transverse row of vertically oscillatory arms mounted on said frame, said arms extending longitudinally of said frame, vertical members secured to and projecting downwardly from said arms to penetrate the material over which the machine is propelled, said members being disposed in at least two rows extending transversely of the machine, the members of one row projecting downwardly to a greater extent than those of the other row to more deeply penetrate said material, and means on said frame and connected with said arms for continuously and relatively oscillating said arms to an extent to force said members into and withdraw them from said material. 15 20 25
10. A machine of the class described comprising a mobile frame for propulsion over loose or plastic road material or the like, a transverse row of vertically oscillatory arms mounted on said frame, said arms extending longitudinally of said frame, vertical plates secured to and projecting downwardly from said arms to penetrate the material over which the frame is propelled, said plates being disposed in end-to-end relation in at least two rows extending transversely of the machine, the plates of one row projecting downwardly to a greater extent than those of the other row to more deeply penetrate said material, and means on said frame and connected with said arms for continuously and relatively oscillating the latter to such an extent as to force said plates into and withdraw them from said material. 30 35 40 45
11. A machine of the class described comprising a mobile frame for propulsion over loose or plastic road material or the like, a transverse row of vertically oscillatory arms mounted on said frame, said arms extending longitudinally of said frame, vertical plates secured to and projecting downwardly from said arms to penetrate the material over which the frame is propelled, said plates being disposed in end-to-end slightly overlapped relation in at least two rows extending transversely of the machine, the plates of one row projecting downwardly to a greater extent than those of the other row to more deeply penetrate said material, and means on said frame and connected with said arms for continuously and relatively oscillating the latter to such an extent as to force said plates into and withdraw them from said material. 50 55 60 65
12. A machine of the class described comprising a mobile frame for propulsion over loose or plastic road material or the like, a transverse row of vertically oscillatory arms mounted on said frame, said arms extending longitudinally of said frame, a plurality of downwardly projecting blades carried by each of said arms and spaced apart transversely thereof to penetrate the material over which the machine is propelled, and means on said frame and connected with said

arms for continuously and relatively oscillating said arms to such an extent as to force said blades into and withdraw them from said material.

5 13. A structure as specified in claim 12; together with a second plurality of downwardly projecting blades carried by each of said arms and spaced apart transversely thereof, the blades of one plurality being staggered with respect to 10 those of the other plurality and being of a different length, and means on said frame and connected with said arms for continuously and relatively oscillating the latter.

14. A machine of the class described comprising 15 a mobile frame for propulsion over loose or plastic road material or the like, groups of vertically movable tamping and mixing members mounted thereon and spaced apart transversely thereof to penetrate said material to a substantial 20 depth, a plurality of vertically movable tamping plates mounted on said frame and located one behind each group of said spaced tamping and mixing members, said tamping plates being disposed in vertical transverse planes and being at least as 25 long transversely of the machine as the groups of members behind which they are located, and means for vertically reciprocating said spaced tamping and mixing members and said tamping plates, the lower edges of said plates being so 30 located as to penetrate and tamp the surface material.

15. A road material mixing machine comprising 35 a mobile frame, a material mixing device mounted thereon for vertical movement, a sleeve connected with said device and projecting up-

wardly therefrom, said sleeve having a closed lower end and also having a closure at its upper end formed with a central opening, a vertical connecting rod extending slidably into said sleeve through said opening of said closure, an abutment on said connecting rod within said sleeve to abut said closure and lift said sleeve and device as the connecting rod is lifted, a compression spring in said sleeve abutting said abutment and closed lower end of said sleeve to downwardly 10 force said device yieldably as the connecting rod is lowered, and means connected with the upper end of said connecting rod for reciprocating the same.

16. A machine of the class described comprising 15 a mobile frame, a tamping or similar device mounted thereon for vertical movement, a sleeve connected with said device and projecting upwardly therefrom, said sleeve having a closure at its upper end formed with a central opening, a 20 vertical connecting rod extending slidably into said sleeve through said opening, an abutment on said connecting rod within said sleeve to abut said closure and lift said sleeve and device as the connecting rod is lifted, a compression spring in 25 said sleeve abutting said abutment to downwardly force said device yieldably as the connecting rod is lowered, and means connected with the upper end of said connecting rod for reciprocating the same, said abutment including a collar 30 detachably secured on said connecting rod, permitting substitution of a collar of different thickness to change the extent of compression of said spring.

BENJAMIN H. FLYNN. 25
